UNITED STATES PATENT OFFICE

2,151,467

PAPERHANGER'S FOLDING STRAIGHTEDGE

Clarence W. Harsin, Los Angeles, Calif.

Application January 31, 1938, Serial No. 187,887

3 Claims. (Cl. 33—107)

This invention relates to a paper hanger's folding straight edge and may be considered an improvement over the construction disclosed in my prior United States Letters Patent No. 1,535,917, issued April 28, 1925.

In my prior patent there is disclosed a paper hanger's folding straight edge consisting of two elongated sections arranged in end-to-end relationship and hingedly connected together where-
5 by the sections may assume a collapsed position wherein one section overlies the other or an ex-
tended position wherein the sections are arranged in alignment and locked in this position by means of a locking bar slidable in guides recessed in the
10 bodies of the sections. In the construction dis-
closed therein a conventional type of hinge was
employed to hingedly connect the sections to-
gether and when this hinge was properly mount-
ed, the knuckles projected slightly above the sur-
15 face of the sections. Also, the guides for the lock-
ing bar were fastened in their respective recesses
in the sections by means of screws.

Disadvantages of this construction became ap-
parent with continued use in that the projecting
20 knuckles of the hinges were objectionable and
with continued use, the screws that attached the
guides in their recesses in the bodies of the sec-
tions had a tendency to loosen and to interfere
with the sliding of the locking bar.

30 It is an object of the present invention to pro-
vide an improved paper hanger's folding straight
edge wherein an improved form of hinge is used
that would eliminate the objectionable projections
and wherein the guides for the locking bar are so
35 constructed and installed as to avoid the use of
screws, nails, or equivalent fastening devices so
that these fastening devices cannot loosen or
interfere with the sliding of the locking bar.

With the foregoing and other objects in view,
40 which will be made manifest in the following de-
tailed description and specifically pointed out in
the appended claims, reference is had to the ac-
companying drawing for an illustrative embodi-
ment of the invention, wherein:

45 Figure 1 is a top plan view of the improved
straight edge in an extended position, illustrating
the locking bar as having been partially slid into
locking position;

Fig. 2 is a partial view of the edge of the straight
50 edge illustrating the nature of the hinge employed
and may be considered as having been taken in
the direction of the arrow 2 upon Fig. 1;

Fig. 3 is an edge view of the straight edge illus-
trating the straight edge in collapsed or folded
55 position; and

Fig. 4 is a view in end elevation of the straight
edge when in collapsed position and may be con-
sidered as being taken in the direction of the
arrow 4 upon Fig. 3.

Referring to the accompanying drawing where-
5 in similar reference characters designate similar
parts throughout, the improved straight edge con-
sists of two elongated sections 10 and 11 prefer-
ably formed of wood or similar material. These
sections are arranged end to end and are provided 10
at their edges with metal wear strips indicated at
12 which may be fastened such as by screws 13.
The wear strips preferably cover the entire edges
of the sections and in the preferred form of con-
struction they slightly project beyond the op- 15
posed faces of the sections 10 and 11 as indi-
cated at 14 on Fig. 4. The sections are hingedly
connected together as by a double or concealed
hinge generally designated at 15. Each hinge
comprises two body parts 16 and 17 which are 20
recessed in the sections 10 and 11 and disposed
inwardly of the adjacent ends of the wear strips
12. The body parts are connected by links 18
which are pivotally connected as by pintles 19
and 20 so that, in effect, there is a double hinge 25
in that each link 18 has two pivots. This con-
struction is such as to enable the two sections 10
and 11 to fold relatively to each other and to as-
sume a position, as shown in Fig. 3, where one
30 section overlies the other. The links 18 being re-
cessed in the body parts 16 and 17 it will be noted
that no portion of the hinge projects up above
the surface of the sections 10 and 11 when the
straight edge is unfolded as shown in Fig. 1. It
35 will be noted that the upper opposed edges of the
sections are rounded over to permit the sections
to be folded so that their upper surfaces will be
opposed. The lower edges are not rounded and
are adapted to abut when the sections are ex-
40 tended. Guides 21 and 22 are recessed in the
upper opposed faces of the sections 10 and 11.
The guide 21 extends approximately half the
length of the section 11 while guide 22 extends
from end to end of section 10. These guides re-
45 ceive and retain a sliding locking bar 23 which is
equal in length to section 10 so that it may as-
sume a position wholly within that section or it
may be slid into a position wherein the locking
bar is partially disposed within section 11 and 50
partially disposed within section 10 so as to lock
the sections in extended and aligned positions.
On sliding the locking bar 23 to the right from
the position shown in Fig. 1 so as to assume a
position wholly within section 10 the straight 55

edge is unlocked and is capable of being folded into the position shown in Fig. 3.

A feature of the invention resides in the construction of the guides 21 and 22. Each guide is formed of an elongated section of sheet metal bent to provide a back or bottom 24, the side edges of which are reversely folded as at 25 to provide outwardly extending flanges. The side edges are then bent upwardly as indicated at 26 forming sides for the guide, and finally, they are bent inwardly to provide inwardly extending flanges 27 which overlie the top of the locking bar. The guide 21 is made approximately one-half as long as guide 22 but otherwise both guides are similarly shaped. The opposed faces of the sections 10 and 11 are recessed to receive these guides and are grooved as indicated at 28 so as to receive the flanges formed by the reverse folds at 25. When the sections 10 and 11 are thus formed, the guides 20 21 and 22 are inserted by being forced endwise into the recesses and into the grooves 28. No screws or other fastening devices are used to attach these guides in position except small brads 29 may be driven through the body of section 10 and through the ends of the flanges on guide 22 to prevent guide 22 from sliding out of its grooves. It is unnecessary to use any fastening devices for guide 21.

From the above-described construction, it will be appreciated that in the improved paper hanger's folding straight edge the construction of the hinge is such that no portion thereof projects when the straight edge is unfolded. Furthermore, as there are no screws or other fastening devices driven through the bottom or back 24 of the guide, these screws cannot loosen under continued usage to interfere with the sliding of the locking bar 23.

Various changes may be made in the details of construction without departing from the spirit or scope of the invention as defined by the appended claims.

I claim:

1. A folding straight edge comprising two elongated sections arranged end to end, means hingedly connecting the sections, guides recessed in the sections, a locking bar slidable in the guides adapted to assume a position wholly within one section or a position partially within each section, each guide providing sides, a bottom, flanges overlying the locking bar, and anchoring flanges recessed in the bodies of the sections.

2. A folding straight edge comprising two elongated sections arranged end to end, means hingedly connecting the sections, guides recessed in the sections, a locking bar slidable in the guides adapted to assume a position wholly within one section or a position partially within each section, each guide providing a bottom, sides, and flanges at the tops of the sides overlying the locking bar, and anchoring flanges at the bottom of the sides which anchoring flanges are recessed in the bodies of the sections.

3. A folding straight edge comprising two elongated sections arranged end to end, means hingedly connecting the sections, guides recessed in the sections, a locking bar slidable in the guides adapted to assume a position wholly within one section or a position partially within each section, each guide being formed of sheet metal bent to provide a bottom having reverse folds at its side edges forming anchoring flanges, sides, and inwardly extending flanges at the tops of the sides overlying the locking bar.

CLARENCE W. HARSIN.
